[57] CLAIM

The ornamental design for a toy telephone, as shown and described.

DESCRIPTION

FIG. 1 is a top left front perspective view of a toy telephone showing our new design; the broken lines showing of a telephone handset and buttons are for illustrative purposes only and form no part of the claimed design;

FIG. 2 is a top plan view thereof;

FIG. 3 is a left side elevational view thereof;

FIG. 4 is a front elevational view thereof;

FIG. 5 is a rear elevational view thereof;

FIG. 6 is a right side elevational view thereof; and,

FIG. 7 is a bottom plan view thereof.
